[57] **CLAIM**

The ornamental design for a window for welder's helmet, as shown and described.

DESCRIPTION

FIG. 1 is a view in perspective of my new design for a window for welder's helmet shown with its upper element down;

FIG. 2 is a top view thereof;

FIG. 3 is a view in front elevation thereof with the upper element raised;

FIG. 4 is a side view thereof;

FIG. 5 is a bottom view thereof;

FIG. 6 is a rear view of the window shown upside-down; and

FIG. 7 is a cross-sectional view taken on line 7—7 of FIG. 6.

FIG. 1

FIG. 2

FIG. 3

FIG. 4

FIG. 5

FIG. 6

FIG. 7
